UNITED STATES PATENT OFFICE.

CONROY WILLIAM DOYLE AND CHARLES FREDERICK ROTHWELL, OF COLUMBUS,
MONTANA.

TIRE-TOOL.

1,238,649

Specification of Letters Patent. Patented Aug. 28, 1917.

Application filed April 24, 1917. Serial No. 164,112.

To all whom it may concern:

Be it known that we, CONROY WILLIAM DOYLE and CHARLES FREDERICK ROTHWELL, citizens of the United States, and residents 5 of Columbus, in the county of Stillwater and State of Montana, have invented new and useful Improvements in Tire-Tools, of which the following is a specification.

Our invention is an improvement in tire 10 tools, and has for its object to provide mechanism of the character specified, for use with quick demountable tires, for collapsing the rim to permit the easy removal of the tire.

15 In the drawings:

Figure 1 is a perspective view of a portion of a rim showing the manner of using the tool;

Fig. 2 is a side view of one of the clamps, 20 with parts in section; and

Fig. 3 is a perspective view of one of the gripping jaws.

The present embodiment of the invention is shown in connection with the split ends 25 of a rim 1, and the improved tool is connected to the rim on opposite sides of the split, to collapse the same. The tool comprises a pair of similar clamps, which are connected by a turn buckle. Each of the 30 clamps consists of a pair of clamping jaws, each consisting of a body 2 having at one end a downwardly and outwardly extending arm 3, which is provided at its free end with an inwardly extending lugs or hook 4 for gripping the edge of the rim. The body portions 2 of the clamping jaws are cylindrical, and they are received within the cylindrical bore 5 of a gripping jaw 6. This jaw 6 is designed to engage the inner 35 face of the tire, and at its ends is a series of teeth or corrugations 7, each series consisting of two portions, the portions facing in opposite directions. The body portions 2 of the clamping jaws are cored, and a coil 45 spring 8 is arranged within the said body portions, each end of the spring being connected with a holding clip or button 9, which engages the outer end of the body portion 2 to hold the spring in place. It 50 will be obvious that the spring will act to draw the clamping jaws toward each other, to cause them to clasp the rim. One of the clamping jaws is provided with a loop

or finger piece 10 for convenience in handling the same, and the gripping jaw of each clamp has an upwardly extending lug 11 at its center. These lugs are connected by a turn buckle, consisting of the usual double nut 12 and the oppositely threaded rods 13 which are pivoted at their ends to 60 the lugs 11.

In use, the clamps are engaged with the rim, by grasping the gripping jaw in one hand. The clamps may be engaged by engaging one of the hooks over one edge of 65 the rim, and drawing the other clamping jaw outwardly, until the hook 4 thereof will engage over the other edge of the rim. After the clamps are engaged, the nut 12 is turned, in the proper direction, to expand or contract the tire. The clamps 70 grasp the rim firmly, and there is no tendency of the same to loosen under stress.

We claim:

1. A tire rim tool including a turn buckle 75 and its rods, and a pair of clamping members pivotally connected to the rods and adapted to be secured to the ends of the split rim, each of said clamping members consisting of a substantially cylindrical 80 gripping jaw having a radial lug intermediate its ends to which the adjacent rod is pivoted, and having at each end a series of gripping teeth, a clamping jaw at each end of the gripping jaw, each clamping jaw 85 consisting of a body portion engaging within the bore of the gripping jaw, and a hook for engaging the edge of the rim, a spring normally drawing the two jaws together, 90 one of the said jaws having a handle portion.

2. In a tool of the character specified, a clamping member consisting of a gripping jaw of substantially cylindrical form adapted to extend transversely of a rim, and 95 spring actuated jaws in connection with the gripping jaw for gripping the rim, each of the said clamping jaws consisting of a hook mounted to slide in the gripping jaw, and a spring normally drawing the clamp- 100 ing jaws together.

CONROY WILLIAM DOYLE.

CHARLES FREDERICK ROTHWELL.
